UNITED STATES PATENT OFFICE.

JAMES A. SWINEHART, OF AKRON, OHIO.

PROCESS OF MAKING TIRES.

1,366,220.

Specification of Letters Patent. Patented Jan. 18, 1921.

Application filed December 16, 1914. Serial No. 877,508.

To all whom it may concern:

Be it known that I, JAMES A. SWINEHART, a citizen of the United States, residing at the city of Akron, in the county 5 of Summit and State of Ohio, have invented certain new and useful Improvements in Processes of Making Tires, of which the following is a specification.

This invention relates to tires and a process 10 of making same and has for its object to provide a cord-tire for automobile wheels and the like which is simple in construction and which has a cord or a cord-like basis of the character and construction herein- 15 after more particularly described about which the tire is built.

A further object of the present invention is to provide a method for winding a cord or a cord-like member upon a pair of side 20 supports to form the basis for said tire, and to provide a removable card or frame adapted to space said supports apart while said member is being wound about said side supports.

Another object of the present invention is to provide means for folding said basis formed of said cord or cord-like member upon itself to form said basis into a net-like 25 structure.

Other objects of this invention are set forth in this specification and, furthermore, this invention consists, also, in the combination and arrangement of parts and the process hereinafter more particularly set 30 forth in this specification and pointed out in the claims.

In the accompanying drawings forming part of this specification wherein like numbers of reference denote like parts wherever they occur,

Figure 1 is a plan view showing the cord or cord-like member wound upon the side supports, the removable card or frame adapted to space said supports apart during the winding process having been removed;

Fig. 2 is a plan view showing the said side supports moved relatively to each other to dispose the course of the windings of 45 said cord or cord-like member at an angle to said side-supports;

Fig. 3 is a plan view showing the wound basis, Fig. 2, folded upon itself over a supporting member to form a net-like structure;

Fig. 4 is a fragmentary plan view on an enlarged scale showing an alternate form of construction for folding the wound basis, Fig. 2, upon itself over a pair of supports to form a net-like structure; 60

Fig. 5 is a fragmentary cross sectional view showing a hinged removable card or frame in place spacing apart the side supports of said cord or cord-like member, and showing, also, a manner of removing said 65 card or frame, the wound cord or cord-like member being shown diagrammatically;

Fig. 6 is a cross-sectional view through the side supports of the cord or cord-like basis, said basis being shown in a diagrammatic view, before folding same to form the net-like structure, the spacing card having been removed;

Fig. 7 is a cross-sectional view showing the relative positions of the side supports 75 and the fold support of Fig. 3;

Fig. 8 is a cross-sectional view showing the relative positions of the side supports and the pair of fold supports of Fig. 4;

Fig. 9 is a fragmentary cross-sectional 80 view of a completed tire showing the net-like basis and its supports illustrated in Fig. 3, in place in said tire; and

Fig. 10 is a cross-sectional view showing the net-like basis and its supports illustrated in Fig. 4, in place in a completed tire.

A pair of flexible tubes 1 of any suitable material, such, for instance, as rubber, may each be provided with a straight wire 90 or the like 2 passed through the opening of each of said tubes, respectively, the ends of said wires preferably extending beyond the ends of said tubes, as shown, for instance, in Fig. 1, tubes 1 being of suitable 95 lengths adapted to the circumference of the tire to be manufactured.

Card or frame 3, Fig. 5, of any suitable material, such, for instance, as wood or metal, is removably placed between the pair 100 of tubes 1 and is adapted to space said tubes apart sufficiently for the construction of a tire of the desired diameter. Card 3 may bear a groove 4 at each of its lateral edges, said grooves being adapted to receive there-in the adjacent curved portions of the outer surfaces of tubes 1, and for conveniently removing said card from the position shown in the solid lines, Fig. 5, said card may be divided along its length into two portions, 110

as shown in said Fig. 5, and said portions attached in hinged relation to each other by any suitable means, such, for instance, as by means of one or more hinges 5.

5 Upon said pair of tubes 1, supported spaced apart by card 3, a cord or cord-like member 6 of any suitable material is wound from one tube to the other continuously and progressively substantially from one of the 10 ends of said tubes to the other ends of said tubes, and when said cord or cord-like member 6 has been so wound, card or frame 3 may be removed by swinging the two parts thereof toward each other upon hinging 15 means 5 as shown in dotted lines, Fig. 5, whereupon said card or frame may readily be withdrawn from between said tubes 1 and said wound cord or cord-like member 6, leaving said wound cord or cord-like member supported upon said tubes substantially as shown in Fig. 1.

Tubes 1 may then be moved longitudinally to such positions relative to each other that the general trend of cord or cord-like member 6 between said tubes is disposed on an incline substantially at an angle of forty five (45) degrees to said tubes as shown in Fig. 2. A flexible tube 7 with a wire 8 therethrough, said wire preferably protruding 30 beyond the ends of said tube as shown in Fig. 3, which tube 7 and wire 8 may be similar to tubes 1 and wires 2, may then be placed substantially mid-way between said pair of tubes 1 upon the wound cord or cord-like member 6, and said cord or cord-like member wound as described, may be folded upon said tube 7 bringing the pair of tubes 1 adjacent to each other as shown in Fig. 35, thus forming a net-like structure with portions of said wound cord or cord-like member 6 crossing the direction of other portions of said wound cord or cord-like member at substantially a right-angle, as shown in Fig. 3.

40 45 Before folding wound cord or cord-like member 6 from the position shown in Fig. 2, to the position shown in Fig. 3, a strip of rubber (not shown, except in the finished state at 9, Figs. 9 and 10) of substantially 50 half the width between the pair of tubes 1, Fig. 2, may be placed upon the windings of cord or cord-like member 6, one longitudinal edge of said strip being adjacent either to one or the other of said pair of tubes, said 55 strip being adapted to supply sufficient rubber to fill the spaces between the windings of said cord or cord-like member, and when said wound member is folded over as shown in Fig. 3, said rubber strip will be between 60 adjacent folded-over portions of said wound cord or cord-like member.

In order to hold the wound cord or cord-like members in place upon tubes 1, and, also, in order to hold said wound cord or 65 cord-like member in place upon tube 7 when

folded to form the net-like structure, Fig. 3, a cement of any suitable composition may be applied to the outer surface of said tubes 1 before said cord or cord-like member 6 is wound thereon, and to the outer surface of tube 7 before said wound cord or cord-like member is folded, as shown in Fig. 3, over said tube 7.

Card or frame 3 may be made of any desired width sufficient to space the pair of tubes 1, Fig. 1, apart at such distance from each other, that when the structure depicted in Fig. 2 is folded to form the net-like structure of Fig. 3, the corded space between tubes 1 and tube 7, Fig. 3, will be adapted to the 80 diameter of the tire desired to be constructed upon or about said net-like structure.

Tubes 1 and 7 and wires 2 and 8 in the net-like structure, Fig. 3, may be formed in the circular shape of the tire to be constructed upon a suitable form after said wound cord or cord-like member 6 has been folded, as hereinabove described to form said net-like structure, and each protruding end of wires 2 and 8 may, after being shortened 90 or cut to proper length to conform to the inner or base circumference of the tire, be welded or mechanically fastened to a corresponding protruding end of wires 2 and 8, respectively, to maintain said wires and said 95 tubes supporting said net-like structure in a closed circular shape. If desired, however, said straight wires 2 and 8 may be removed from tubes 1 and 7, respectively, after the net-like structure, Fig. 3, has been formed, 100 and then wires previously formed in circular shapes adapted in circumference to the circumference of the tire to be manufactured may be threaded through said tubes and the adjacent cut-ends of said wires may be 105 welded or mechanically fastened together, and thus the desired circular supports for the corded structure for the basis of a tire may be obtained.

The net-like structure, Fig. 3, supported 110 by tubes 1 and 7, formed into the desired circular shapes, as above described, may then be placed with one or more layers of fabric, rubber, and the like in a full cure-mold of any desired construction and cured in any 115 suitable manner to form a completed tire, such, for instance as the tire shown in fragmentary cross sectional view, Fig. 9, of the accompanying drawings, wherein the net-like structure, Fig. 3, with tubes 1 and 7 and 120 the wires therethrough are shown in place in a finished tire.

A modified form of folding the corded structure, Fig. 3, to form the net-like structure herein described is depicted in Figs. 4 125 and 8, and said modified form is shown in place in a finished tire in Fig. 10.

In said modified form, instead of folding said corded structure over one flexible tube 7 with wire 8 therethrough, as hereinabove 130

described and as shown in Figs. 3, 7, and 9, two flexible tubes 10 and 11, each tube, respectively, having a wire or the like 12 and 13 therethrough, which tubes 10 and 11 may 5 be similar to tubes 1, and which wires 12 and 13 may be similar to wires 2, said wires 13 and 14 preferably being adapted to have their ends protruding beyond the ends of their respective tubes 10 and 11. Tube 10 is 10 inserted in the space between the wound cord or cord-like member 6, Fig. 2, formed by the thickness of tubes 1 and tube 11 is placed against an outside portion of said cord or cord-like member, each of said tubes being 15 substantially mid-way between tubes 1. The structure, Fig. 2, is then folded over said tubes 10 and 11, and one tube 1 placed adjacent to the other tube 1 to form a net-like structure, Fig. 4, with the cording of one 20 portion traversing the direction of the cording of an opposite adjacent portion at substantially a right-angle. In this modified form, also, cement of any suitable composition may be applied to tubes 1 and to tubes 25 11 and 12 to hold said cord or cord-like member 6 in place thereon, and, before folding to form the net-like structure, Fig. 4, a strip of rubber (not shown except in the finished tire at 9. Fig. 10) of substantially half the 30 width between the pair of tubes 1, Fig. 2, may be placed upon the corded structure, one edge of said strip being adjacent either to one or the other of said pair of tubes, said strip being adapted to supply sufficient rubber 35 to fill the spaces between the windings of said corded structure.

The desired circular form for the construction of the tire may be given to tubes 1, 10, and 11 in the modified form of folded net-like structure in a manner similar to that described in describing the manner of giving circular form to tubes 1 and 7 of Fig. 3, and said net-like structure, Fig. 4, may then be placed with one or more layers of fabric, 45 rubber, and the like in a full-cure mold of any desired construction and cured in any suitable manner to form a completed tire, such, for instance, as the tire shown in cross sectional view, Fig. 10, of the accompanying drawings, wherein the net-like structure, 50 Fig. 4, with tubes 1, 10, and 11 with the wire through same are shown in place in a finished tire.

It is preferred to cure a tire constructed 55 with the net-like structure of Figs. 3 or 4 of the present invention in a mold with a flexible core designed to be expanded by a fluid, such as the mold described in this applicant's application for patent for method 60 of making tires and apparatus therefor, filed in the United States Patent Office May 16, 1913, bearing Serial Number 767,960, which application was allowed by the Patent Office on June 23, 1914, Patent No. 65 1,122,333. However, any other suitable form

of mold or process of curing may be used in constructing a tire embodying the present invention.

Various changes in the combination and arrangement of parts may be made without departing from the nature and spirit of the present invention.

I claim:

1. The herein-described process of winding a cord-like member for a cord-tire upon 75 a pair of spaced flexible members, the cord-like members being spaced apart and the said flexible members being held apart during the winding process by means of a rigid card removably placed therebetween, said 80 flexible members being shifted longitudinally with reference to each other in such manner as to place said card members at an angle to said flexible members.

2. The herein-described process of winding a cord-like member for a cord-tire upon 85 a pair of spaced flexible members, the said cord-like members being spaced apart, said flexible members being held apart during the winding process by means of a card removably placed therebetween, said flexible members being shifted longitudinally with 90 reference to each other in such manner as to place said cord members at an angle to said flexible members, said card being of a width 95 sufficient to permit said wound cord-like member to be doubled upon itself in such manner as to form a net of a width adapted to the diameter of a tire.

3. The herein-described process of winding a cord-like member for a cord-tire upon 100 a pair of spaced flexible members, said cord-like members being spaced apart, said flexible members being held apart during the winding process by means of a card removably placed therebetween, said flexible members being shifted longitudinally with 105 reference to each other in such manner as to place said cord members at an angle to said flexible members, said wound cord-like member being doubled upon itself by means of a third flexible member being placed between the two first-named flexible members, thereby forming a net of a plurality of thicknesses of the said cord-like members.

4. The herein-described process of winding a cord-like member for a cord-tire upon 110 a pair of spaced flexible members, said flexible members being held apart during the winding process by means of a card removably placed therebetween, said flexible members being shifted longitudinally with reference to each other in such manner as to place said cord members at an angle to said flexible members, said card being of a width 115 sufficient to permit said wound cord-like member to be doubled upon itself to form a net of a width adapted to the diameter of a tire.

5. The herein-described process of wind-

ing a cord-like member for a cord-tire upon a pair of spaced hollow flexible members, said flexible members being held apart during the winding process by means of a card 5 removably placed therebetween, said wound cord-like member being then folded over a third hollow flexible member placed intermediate said pair of hollow flexible members, said folded wound cord-like member 10 forming a netting, said hollow flexible members being then shaped in circular form adapted to the circumference of the tire by means of threading ring-shaped wires through the hollow portion of said hollow members and embedding said netting with 15 said hollow members within the structure of the tire before curing said tire.

6. The herein-described process of winding a cord-like member for a cord-tire upon 20 a pair of spaced hollow flexible members, said flexible members being held apart during the winding process by means of a card removably placed therebetween, removing said card from between said hollow members folding said wound cord-like member upon itself over hollow flexible means with a rubber strip between the folded-over portion of said cord-like member, said folded wound cord-like member forming a netting of a 25 width adapted to the diameter of the tire and then shaping said hollow flexible members and said hollow flexible means in circular form adapted to the circumference of the tire by means of threading ring-shaped 30 wires through the hollow portions of said hollow members and said hollow means, placing said netting, rubber-strip, hollow members, hollow means, and said wires between a plurality of layers of rubber, fabric, 35 and the like, in a mold to form a tire and curing the tire by expanding same with a flexible core adapted to expand either by 40 fluid or any mechanical means.

7. The herein-described process of making 45 a tire or tire-shoe which consists in forming a strength-giving fabric by winding a cord-like member spirally about a pair of spaced suitably-supported hollow tube-like members, folding said fabric about an anchor near the median line thereof, placing 50 reinforcing members in said tube-like members, bringing the ends of said reinforcing members together and connecting them thereby to fashion the fabric into annular 55 formation, incorporating said folded fabric in the body of a tire or tire-shoe with the tube-like members disposed in one of the beads and the reinforcing member positioned in the other bead, and curing the tire 60 or shoe in a confining medium and simultaneously expanding the wall of said tire-shoe by an interiorly-positioned expandible flexible core during the curing operation.

8. The herein-described process of making 65 a tire or tire-shoe which consists in forming

a cord-like fabric by spiral convolutions of a flexible member about a pair of spaced tube-like members, folding said fabric about an anchor positioned near the median line thereof, threading reinforcing members 70 through said tube-like members, connecting the ends of said reinforcing members thereby to fashion the fabric into annular formation, positioning said folded fabric in the body of a tire or shoe with the tube-like 75 members and reinforcing members positioned in the beads, and curing the tire or shoe in a mold by the employment of an expansible flexible core positioned within the tire or shoe and expanded therein during the 80 curing operation.

9. A method of manufacturing pneumatic tires including the following steps, namely, forming an annular substantially flat body material of cord strands, by winding cord-like members about a pair of spaced tube-like members, subsequently folding said body about a third tube-like member to form a body portion of less width than the first-mentioned body, placing an air-bag within 90 said body portion, applying fluid pressure to the interior of said air bag, and finally curing the tire while thus under internal pressure.

10. The herein-described process of making 95 a tire or tire-shoe which consists in forming a strength-giving fabric by winding a cord-like member spirally about a pair of spaced suitably-supported hollow tube-like members, folding said fabric about an anchor near the median line thereof, placing reinforcing members in said tube-like 100 members, bringing the ends of said reinforcing members together and connecting them thereby to fashion the fabric into annular 105 formation, incorporating said folded fabric in the body of a tire or tire-shoe with the tube-like members disposed in one of the beads and the reinforcing member positioned in the other bead, inclosing the outer 110 portion of the tire or tire-shoe by a non-yielding wall of suitable material, and simultaneously expanding the wall of said tire or tire-shoe against said wall by an interiorly-positioned expandible instrumentality during the vulcanizing operation.

11. The herein-described process of making 115 a tire or tire-shoe which consists in forming a cord-like member by winding a flexible member about a pair of spaced hollow flexible members, said members being held apart during the winding process, folding said woundup cord-like member upon itself over an anchor positioned along the median line between said hollow members, 120 superposing a strip between the folded-over portions of said cord-like member, said folded wound cord member forming a netting of a width adapted to fit a tire 125 or shoe, and then shaping said hollow 130

members and anchor into circular form suitable for a tire or tire shoe, threading reinforcing wires through said hollow members, joining their ends, positioning said structure so formed in the body of a tire or shoe, and curing the same in a mold by the employment of an expansible flexible core adapted to expand within said tire or shoe either by fluid or any mechanical means.

12. The herein-described process of making a tire or tire-shoe which consists in forming a cord-like member by winding a flexible member about a pair of spaced hollow flexible members, said members being held apart during the winding process, folding said woundup cord-like member upon itself over an anchor positioned along the median line between said hollow members, superposing a strip between the folded-over portions of said cord-like member, said folded wound cord member forming a netting of a width adapted to fit a tire or shoe, and then shaping said hollow members and anchor into circular form suitable for a tire or tire shoe, threading reinforcing wires through said hollow members, positioning said structure so formed in the body of a tire or shoe, and curing the same in a mold

by the employment of an expansible flexible 30 core adapted to expand within said tire or shoe either by fluid or any mechanical means.

13. The herein described process of winding a cord-like member for a cord-tire upon 35 a pair of spaced flexible members, the windings of said cord-like member being spaced apart, said flexible members being held apart during the winding process by means of a card removably placed therebetween, said 40 wound cord-like member to be doubled upon itself by means of placing a third flexible member at approximately midway between the first two named flexible members and folding said cord-like member over the said 45 third flexible member in such manner as to cause the strands of the said cord-like member to intersect the meshes formed by said cord member thereby forming a net composed of a plurality of thicknesses of the 50 said cord-like member.

In testimony whereof I hereunto affix my signature in the presence of two witnesses.

JAMES A. SWINEHART.
